UNITED STATES PATENT OFFICE.

ROBERT HERZOG, OF BERLIN, AND LEO FUNGS, OF BERLIN-CHARLOTTENBURG, GERMANY, ASSIGNORS TO C. LORENZ AKTIENGESELLSCHAFT, OF LORENSWEG-BERLIN-TEMPELHOF, GERMANY.

RADIO SIGNALING SYSTEM.

Application filed August 23, 1921. Serial No. 494,516.

To all whom it may concern:

Be it known that we, ROBERT HERZOG, residing at Berlin, Germany, and LEO FUNGS, residing at Berlin-Charlottenburg, Germany, both citizens of Germany, have invented certain new and useful Improvements in Radio Signaling Systems (for which I have filed applications in Germany on the following dates, July 15, 1919, August 5, 1919, September 16, 1919, and April 1, 1920), of which the following is a specification.

This invention relates to a key connection for the purposes of the wireless transmission of messages which permits to control large energies free from sparks and without disturbance of the high frequency generator. The invention is consequently specially adapted for such generators in which the chief object is the production of absolutely constant oscillations which can be easily influenced by the control.

In the novel connection a transformer is laid parallel to the generator, a condenser for taking up the non-radiated energy being inserted at the same time in this parallel branch. An independent transformer is connected in the earth circuit, but the two transformers are not continuously energized. The secondary windings are inserted in the parallel branch to the generator or in the earth connection whilst the primary windings are connected with the sender. The sender short-circuits either the primary winding of the transformer inserted in the parallel branch of the generator or the primary winding of the transformer inserted in the earth connection so that a connection is produced according to the example illustrated on the drawings.

Figure 1 is a diagrammatic sketch of a transmitting circuit arranged in accordance with the invention and employing two regulating transformers,

Figures 2, 3 and 4 are similar diagrams showing different hook-ups requiring the use of only one regulating transformer.

On Fig. 1 g is the generator, which can consist for instance of a Poulsen arc, with block condensers c_1 , c_2 . A key condenser c_3 is inserted in the parallel branch and series-connected with the primary winding of the transformer t_1 . The primary winding of

the transformer t_2 is inserted in the earth connection. The transformers t_1 and t_2 are preferably with closed magnetic circuit and they possess each two windings, the primary winding comprising many turns of a thin wire and the secondary winding comprising few turns of a thick wire. The secondary windings are connected with the key in such a manner that no high frequency oscillations are radiated in the position shown as the oscillations produced by the generator g travel over c_1 , c_3 , winding w_1 , c_2 . The key a short-circuits the secondary winding of the transformer t_1 so that the choking effect of the primary winding is neutralized and the condenser c_3 takes up the output from the generator g . The oscillations circuit c_1 , c_3 , w_1 , c_2 is earth connected. When transmitting signs the key is short-circuited by the secondary winding w_2 of the transformer t_2 , the choking effect of the primary coil is neutralized and the oscillations of the generator are radiated whilst the loading condenser c_3 is choked by the primary coil w_1 of the transformer t_1 in which the short-circuit of the primary coil is suspended by the key.

As the example of execution shows the invention consisting in the use of two, not continuous-current magnetized preferably closed magnetic circuited transformers, whose secondary windings are connected with the key in such a manner that, when the key is open as shown in the drawing, the choking effect of the transformer arranged in the parallel branch to the generator is suspended whilst when the key is depressed the secondary winding of the second transformer is short-circuited so that the choking effect of its primary coil is suspended.

The invention can be utilized evidently also in economical transformer connection or with utilization of corresponding strong choking coils without iron. The use of closed magnetic circuited transformers has however the advantage that, owing to the narrow coupling resulting herefrom, comparatively small coils can be used so that the key apparatus, which can be arranged at any transmitting point, are of small dimension and of little weight.

The invention presents the further advantage that an accelerated control of the high

frequency current can be carried through with full security of service so that the key arrangement is adapted specially for rapid service for the control of great energies.

5 The novel key arrangement can be carried out, differing from the form of construction shown on the drawing, in using only one transformer t_1 . In this case there is however no complete interruption of the 10 high frequency current effected so that high frequency current flows in the antenna indicated on the drawing, even at the position of rest.

15 The invention relates further to a key connection in which the choking effect of a transformer is utilized also, only one transformer being however employed, which, according to the position of the key, closes or opens the radiating circuit, the transformer 20 being for instance inserted in the earth connection, or it cuts out this earth connection being cut out when the key is open. The connection must be arranged so that, when the key is open, the generator is in closed 25 circuit and the supply of energy, is not interrupted.

Hitherto the sending of signs has been effected by conducting the high frequency oscillations over a capacity when the key is 30 open.

This method as well as similar methods present the inconvenience that the source of current and the generator are equally loaded. At 35 transmitting with great telegraphing speed the second transformer according to the invention can be avoided by inserting only one transformer in the radiating circuit (antenna). The key is arranged this time in the transformer so that the choking effect of 40 the same is utilized.

Consequently the source of current and the generator are fully loaded during the sending of signs while only very little current is consumed in the intervals. This is 45 rendered possible by the arrangement according to which the generator is situated in a closed circuit when the key is open and the earth connection is cut out.

50 Fig. 2 shows a form of execution of the connection in which the generator g , which can be for instance an arc generator or a machine, is inserted in a circuit consisting of a capacity c_1 and c_2 and self inductance s , in whose earth connection the transformer t with the key a is inserted. The generator 55 can be short-circuited by one capacity or by several series-connected capacities c_s . Instead of the transformer t two choking coils could be used, of which one has an iron core 60 and is alternately short-circuited and cut-in by the key. The arrangement could further be such that the transformer or the choking coils are not directly earth-connected but inserted in the antenna branch.

65 According to the known methods for the

keying of Poulsen-generators either the antenna was desyntonized or the arc was reversed from the antenna to a key circuit which usually consists of a greater capacity and of a resistance and alters as little as possible the ratio of loading. The first method suffers from the defect, that the desyntonizing wave is set out with almost full energy. The second method is complicated by the indispensable interruption of the 70 antenna circuit and the cutting-in of the key circuit, this being connected with great difficulties specially at the rapid telegraphy. 75

The invention has further for its object to avoid these inconveniences, in laying constantly a capacity or a self-induction or a combination of the two parallel to the arc, this capacity being dimensioned so that on the one hand an increase of the efficiency of the arrangement is produced (energy connection) and on the other hand the arc can work exclusively without disturbance upon this parallel circuit without simultaneous cutting out of the antenna. Exhaustive experiments have shown that it is possible to 80 make the arrangement such that the arc is not disturbed and not extinguished during the operation of the key. The key is operated in a simple manner by interrupting the antenna circuit in the intervals between the 85 types and the earth connection whilst during the rotating period the parallel circuit to the arc is not interrupted. A reversing of the arc from one circuit to the other does not take place so that consequently the inconveniences resulting from this are avoided. 90

95 Experiments have further shown that it is not necessary with an arrangement described to maintain constant the loading of the arc generator in order to avoid disturbances or extinction of the arc. It is possible to select the condition so that during the intervals the connection works with small loading so that an economy of energy and in the size of the machine is realized. 100

105 The method can be utilized with special advantage in connection with coils with iron cores whose saturation is varied by superposition of a continuous current magnetization or by short-circuiting of windings. The operation of the key is effected by alteration of the saturation so that all reversals and the alteration itself are suppressed. 110

115 Figs. 3 and 4 show examples of execution of the method.

In Fig. 3 a is the arc which works upon the antenna circuit, b is the auxiliary circuit which is parallel to the arc and which contains for instance the capacity. e is a coil with iron core whose winding c is cut into the earth connection of the antenna whilst the winding d can be short-circuited by a key t . At short-circuiting the field in the coil is suspended so that the antenna takes up the full current. At suppression of the 120

short-circuiting the antenna current is suppressed by the iron core.

According to Fig. 4 an iron coil is used also for the operation of the key but the alteration of the saturation is caused by a continuous current flowing in the winding *d* and closed by the key *t*. The circuit *b* which is parallel to the arc prevents also in this case, same as in the arrangement shown on Fig. 3, that the arc is extinguished at the operation of the key.

I claim:—

1. A high frequency signal transmission system comprising in combination a generator of high frequency oscillations, a radiating circuit connected with said generator, an oscillatory circuit connecting with said generator in parallel relationship to said radiating circuit, a pair of independent transformers each having primary and secondary windings, with the primary winding of one transformer interposed in said oscillatory circuit and the primary winding of the other transformer interposed in said radiating circuit, said secondary windings being connected to have a common terminal and having connections to a keying circuit whereby said primary windings may be alternately made effective as high frequency chokes in accordance with the production of signals.

2. A high frequency signal transmission system comprising in combination a generator of high frequency oscillations, a radiating circuit connected with said generator, an oscillatory circuit connecting with said generator in parallel relationship to said radiating circuit, a pair of transformers each having primary and secondary windings with the primary winding of one transformer interposed in said oscillatory circuit and the primary winding of said other transformer interposed in said radiating circuit, said secondary windings being connected to have a common terminal, a keying system comprising a circuit closing device having front and rear contacts, a connection between the common terminals of said secondary windings and said keying system and connections between opposite ends of said secondary windings with said contacts whereby said keying system may be operated in accordance with signals to alternately shunt said secondary windings.

3. A high frequency signaling system comprising in combination a source of high frequency oscillations, a radiating system, a circuit interconnecting said source of high frequency oscillations with said radiating system, a pair of transformers each having primary and secondary windings with said primary windings connected independently in circuit with said radiating system and in said first mentioned circuit, a common connection between the ends of said secondary windings, a double-acting key having front

and back contacts connected with the opposite ends of said secondary windings, and a key lever connected with said common connection for alternately short circuiting the respective secondary windings for the production of signals.

4. A high frequency signaling system comprising in combination a source of high frequency oscillations, a radiating circuit connected therewith, an oscillatory circuit connected in parallel with said source of high frequency oscillations, a pair of transformers each having primary and secondary windings, with the primary windings of each transformer independently connected in said radiating circuit and said oscillatory circuit respectively, said secondary windings being connected to have a common terminal, a double-acting key having front and back contacts, a key lever for alternately making connections with said front and back contacts, a connection between said key lever and the common terminals of said secondary windings and connections between said front and back contacts with the opposite ends of said secondary windings, whereby said secondary windings may be alternately shunted by said key lever and said contacts for neutralizing the choking effects of said primary windings and enabling said source of high frequency oscillations to be alternately effective upon said radiating circuit or said oscillatory circuit.

5. A high frequency signaling system comprising in combination a source of high frequency oscillations, a radiating circuit connected therewith, an oscillatory circuit connected in parallel with said source of high frequency oscillations, a pair of transformers each having primary and secondary windings with the primary windings of each transformer independently connected in said radiating circuit and said oscillatory circuit respectively, said secondary windings being connected to have a common terminal, a double-acting key having front and back contacts, a key lever for alternately making connections with said front and back contacts, a connection between said key lever and the common terminals of said secondary windings, and connections between said front and back contacts with the opposite ends of said secondary windings, said primary windings each having a plurality of turns of relatively fine wire and normally serving as a choke to the passage of high frequency oscillations, and said secondary windings comprising a relatively small number of turns of heavy wire, whereby upon shunting of ends of said secondary windings the choking effects of said primary windings may be alternately suspended for making effective said high frequency oscillations upon said radiating circuit.

6. In a high frequency signal transmission

system the combination with a source of high frequency oscillations of a radiating circuit, a parallel branch circuit connected with said radiating circuit and with said source of high frequency oscillations, a pair of transformers each having primary and secondary windings, one of said transformers being disposed in the radiating circuit and the other transformer being disposed in the parallel branch circuit, means for shunting either one of said secondary windings when the other of said secondary windings is open, said primary windings each function-

ing as a high frequency choke coil when cooperating secondary windings are open, the choking effects thereof being suspended when the cooperating secondary winding is open, whereby said secondary windings may be opened or shunted in accordance with signals for alternately rendering said source of oscillations effective upon said parallel branch circuit or said radiating circuit. 15 20

In testimony whereof we have signed this specification.
